SELF-LOCKING SAFETY CATCH

Morton Yasnor, Brooklyn, N. Y.

Application February 3, 1945, Serial No. 575,982

1 Claim. (Cl. 24—157)

1

This invention relates to an improved safety catch for pins and brooches, and the like, and one of its objects is to provide a spring pressed safety catch, which can be forced to release or open position, by the pressure of the shank of the pin against the side of the safety catch, and which will then automatically hold the pin in locked position.

Another object of the invention is the provision of a spring pressed safety catch or retainer, with a U-shaped frame, which is pivotally supported against the sides of a keeper by trunnions struck from the sides of the keeper, to close the through or pin entrance of the keeper, and which will yield to open position against the keeper, so as to allow a free entrance for the shank of the pin.

With the above and other objects in view the invention consists in certain new and useful constructions, combinations, and arrangements of parts, clearly described in the following specification, and fully illustrated in the accompanying drawings, in which—

Fig. 1 is a side view of a brooch provided with the improved safety catch.

Fig. 2 is an end view of the safety catch, closed.

Fig. 3 is a similar view, showing the catch open.

Fig. 4 is a detail horizontal sectional view, taken on line 4—4 of Fig. 2, looking in the direction of the arrows.

Fig. 5 is a sectional view, taken on line 5—5 of Fig. 3, looking in the direction of the arrows.

Referring to the accompanying drawings, which illustrate the practical construction of my invention, 5 designates a decorative or face plate of a brooch, or other pin bar, which may be of any form of construction, and which is provided near one end with bearing lug 6, on which the eye 7 of the pin shank 8 is pivoted. This pin shank is provided with the usual pointed end 8a.

On the opposite end of the brooch my improved safety catch 10 is located. This safety catch includes a keeper 11, which is in the form of a narrow strip of metal, and is formed with a base attaching flange 12, and with an overhanging loop 13. The sides of the keeper 11 are formed with integral trunnions 14.

A spring 15, formed of flat spring stock, and provided with a U-shaped loop 16 on its lower end, is secured against the keeper 11 by means of the lug 17, which is struck from one side of the keeper and folded over, as shown in Figs. 4 and 5, against the spring, so as to secure the lower end thereof to the keeper.

A U-shaped rocker or frame 18, which includes the side wings 19 and 20, and the intermediate

2

and connecting safety catch bar or member 21, is hinged by the side wings to swing on the trunnions 14, each of these wings having bearing holes to receive the trunnion it engages. The upper end of the bar or member 21 is slightly deflected at 21a, so as to have full contact with the depending end 13a of the loop 13, and the upper end of the spring 15 is also formed with a bent end portion 15a, which bears against the inner surface of the member or bar 21, and which normally presses the outer surface of the bar or member 21 against the inner surface of the depending end 13a of the loop 13, so as to maintain the pin entrance 22 between the loop end 13a of the keeper 11 normally closed.

The wing 19 of the safety catch frame or rocker 18 is provided with an integral lever arm 23, so that the frame of the safety catch may be manually pressed to open position, against the resistance of the spring 15. This is one way of opening the frame 18. The entrance 22 may also be opened by pressing the end portion of the pin-shank 8 against the side of the rocker or frame 18, to overcome the resistance of the spring 15. When this is done the intermediate bar 21 of the rocker 18 forms a guiding surface for the shank of the pin, which can be moved over the rocker to a point above it, so as to allow the rocker to close by the reaction of the spring 15, to assume the position shown in Fig. 2, when the pin shank will be confined in the loop 13 of the keeper 11.

It is seen, therefore, that my improved safety catch is normally closed or in locked position, so that the shank of the pin cannot be accidentally displaced from under the keeper, and that to release the pin shank, it is necessary to manually force the safety catch to open position, but that it automatically returns to closed or locking position, as soon as manual pressure is released from the swinging or rocking frame 18.

It is understood that various changes in the details of construction, their combination and arrangement may be resorted to, within the scope of the invention, as defined by the claim hereof.

Having described my invention, I claim as new:

A self-locking safety catch, comprising a bar having a base and a hook overlying the base and spaced therefrom, the bar being formed with integral trunnions on the opposite side thereof, a guard having side wings provided with bearing openings which receive the trunnions and provided with a terminal portion which engages the inner side of the hook, said first-named bar having an integral lug disposed in clamping relation thereto, and a flat spring having a hooked lower

end secured by said lug and a curved upper end disposed in pressure engagement with the inner surface of the guard, whereby said guard will be held in pressure contact with the hook, the guard being displaced inward by the pressure of a pin against the same and one of the wings of the guard being formed with an integral lever arm to move the guard against the pressure of the spring.

MORTON YASNOR. 10
